UNITED STATES PATENT OFFICE.

ANDREW E. BLIGHT, OF TOTTENVILLE, NEW YORK.

ROLLER.

939,206.

Specification of Letters Patent. Patented Nov. 9, 1909.

Application filed May 6, 1909. Serial No. 494,256.

To all whom it may concern:

Be it known that I, ANDREW E. BLIGHT, a citizen of the United States, residing at Tottenville, Staten Island, State of New York, have invented certain new and useful Improvements in Rollers, of which the following is a specification.

My invention relates to typewriters and has for its object to provide a means whereby the elasticity and the thickness of the roller commonly used on typewriting machines may be varied.

In the use of the rollers of typewriting machines commonly known in the art it has been found that a typewriting machine will operate best when using a certain number of sheets of paper or using paper of a certain thickness, and, furthermore, it has been found that the rollers commonly used in the art are sometimes made too hard or become too hard by reason of age which often causes the type-hammers to crack and break off. Furthermore the rollers lose their elasticity and become hard and smooth so that the paper cannot be moved as readily and accurately by the turning of the rollers as when typewriting machines containing them were first placed on the market.

My invention provides a means for adjusting the elasticity or cushioning of the roller any time that may be desired, and also provides a means whereby the thickness of the roller may be varied according to the thickness and number of sheets of paper that it is desired to operate upon.

The invention consists in other features illustrated in the drawing, described and referred to in the following description and claimed in the claims:

Referring to the drawings, Figure 1 illustrates a perspective view of the invention and Fig. 2 illustrates a horizontal sectional view.

Referring to Fig. 1, 1 is a heavy tube having a rubber cushioning surface 2. Plugs 3 and 4 are located in the ends of the tube 1 and tightly seal the tube so as to prevent the escape of any air that may be contained in the tube or roller. Heads 5 and 6 are attached to the plugs 3 and 4 by means of screws 7 and 18. The heads 5 and 6 have hollow bearings 8 and 9 which are used in mounting the roller in a typewriting machine. A rod 10 extends through the plugs

and the heads and the bearings and firmly secures the parts together. The rod 10 is hollow in order to make the roller perfectly rigid and give sufficient surface for tightly securing the plug and head of one end of the roller and the plug and head of the other end. The hollow rod 10 extends through the bearings so that it will be directly supported at its ends. The parts of the roller are supported by the hollow tube and the hollow tube is directly supported in the typewriting machine. The head 5 is secured to the hollow rod by means of the screw 17 and the head 6 is forced on the tube 10 by pressure. A valve casing 11 is located in the head 5 and is provided with the usual cap 12 and puppet valve 15. This permits the air to be forced into the roller through the opening 16 in the plug 3 and prevents the return of the air except as the valve 15 may be pressed down by pressing on its stem. The head 6 is provided with the usual ratchet wheel for moving the roller step-by-step when it is desired to shift the paper in the machine in the manner well known in the art. Rings 13 and 14 are forced on to the ends of the roller and around the plugs 3 and 4. This tightly compresses the ends of the roller and the plugs 3 and 4 and further operates to assist in the permanent sealing and closing of the cylinder 1.

In the operation of the device the cushioning surface of the rubber roller frictionally seizes the paper and the surface of the roller being more or less pliable by reason of its pneumatic character it will press the paper around the guide rollers whereby the rubber surface of the pneumatic roller will more perfectly seize the paper and move the paper with the pneumatic roller. The rigidity of the surface of the roller may be varied at will by forcing air into its interior or allowing it to escape. Furthermore the diameter of the roller may be varied at will in the same manner in order that different quantities of paper may be inserted in the machine or paper of different thickness may be operated upon. This permits the roller to press upon the paper uniformly whatever may be the thickness of the sheets or the number thereof and forms an adjustment of the roller to the character of the work that is desired to be accomplished. Furthermore the rigidity of the roller sur-

face may be adjusted so as to obtain varying degrees of sharpness of outline of the letters printed on the paper and yet at the same time the volume of the roller is small, which 5 reduces the rebounding effect on the type-hammer and prevents to a great degree the breaking of the hammer and reduces in a great measure the noise of the machine due to the sharp return of the hammer. Forcing air into the roller causes it to become as hard as it may be desired without changing the mass of the roller and without changing the power of the roller to frictional seizing 10 the paper to a material degree.

15 The invention may be varied by those skilled in the art without departing from the spirit thereof. It may be used in connection with a great many devices wherein the thickness or the pliability or the rigidity of 20 the roller is to be adjusted or varied. It may be in fact embodied in a great many forms of constructions, while yet involving the essence of the invention.

What I claim as new and desire to secure by Letters Patent is as follows—

The combination of a platen having a rubber cushioning surface, plugs pneumatically sealing the said platen, heads attached to said plugs, a valve located in one of the said heads, a hollow rod securely set in and attached to the said plugs and the said heads and extended through the said roller, the extended hollow bearings located on the outside of the said rod, the said hollow rod extending through the said hollow bearings, 30 rings for clenching the said platen to the said plugs and heads whereby the thickness and pliability of the platen may be varied.

In testimony whereof, I have signed my name to this specification, in the presence of 40 two subscribing witnesses.

ANDREW E. BLIGHT.
